(57) **CLAIM**

The ornamental design for a decorative ornament, as shown and described.

DESCRIPTION

FIG. 1 is a perspective view of a decorative ornament according to the present invention.

FIG. 2 is a front view of the decorative ornament of FIG. 1. The rear view, right side view, and left side view are identical to the front view.

FIG. 3 is a top view of the decorative ornament of FIG. 1; and,

FIG. 4 is a bottom view of the decorative ornament of FIG. 1.

The broken lines in all views are for illustrative purposes only and form no part of the claimed design.
